UNITED STATES PATENT OFFICE.

EDITH SPENCER McVICKER, OF VERMILION, SOUTH DAKOTA.

DESIGN FOR A SERVING-TRAY.

52,486.

Specification for Design. Patented Sept. 24, 1918.

Application filed May 14, 1918. Serial No. 234,538. Term of patent 14 years.

To all whom it may concern:

Be it known that I, EDITH S. McVICKER, a citizen of the United States, residing at Vermilion, in the county of Clay and State of South Dakota, have invented a new, original, and ornamental Design for Serving-Trays, of which the following is a specification, reference being had to the accompanying drawing, forming a part thereof.

The figure is a plan view of a serving tray, showing my new design.

I claim:

The ornamental design for a serving tray, as shown.

EDITH SPENCER McVICKER.

Witnesses:

C. H. BARRETT,
F. G. HYDE.
